UNITED STATES PATENT OFFICE.

JAMES HUMES, OF PHILADELPHIA, PENNSYLVANIA.

ICE-MAKING APPARATUS.

1,082,871.

Specification of Letters Patent. Patented Dec. 30, 1913.

Application filed June 17, 1912. Serial No. 704,118.

To all whom it may concern:

Be it known that I, JAMES HUMES, a citizen of the United States, residing in Philadelphia, county of Philadelphia, State of Pennsylvania, have invented certain new and useful Improvements in Ice-Making Apparatus, of which the following is such a full, clear, and exact description as will enable any one skilled in the art to which it appertains to make and use the same, reference being had to the accompanying drawings, forming part of this specification.

My invention relates to certain improvements in apparatus for manufacturing blocks of ice and it has reference more particularly to the can or portable vessel in which the ice-block is formed.

It is the purpose of my invention, as will more fully hereinafter appear, to make the can more durable and to increase its efficiency, and particularly in cases where the ice is formed from raw or undistilled water, though of course distilled water may be used.

My invention is further characterized by having the can with its insulating or freezing-retarding pocket and its air-injecting pipe made as a unitary article of commerce or manufacture.

With these and other objects in view my invention consists in the various novel and peculiar arrangements and combinations of the several different parts of the apparatus, all as hereinafter fully set forth, and then pointed out in the claims.

I have illustrated types of my invention in the accompanying drawings, wherein:

Figure 1 is a perspective view of my improved ice can. Fig. 2 is a central vertical sectional view of the can shown in Fig. 1.

Fig. 3 is a vertical sectional view of an ordinary freezing tank showing one of my ice cans placed therein and with a block of ice formed in the can. Fig. 4 is a top plan view of the ice can with a block of ice formed therein. Fig. 5 is a perspective view of a portion of my improved can, the view showing the pocketed side of the can and a modified form of air-injecting pipe or duct. Fig.

6 is a top plan view of my improved can in which the air pocket is used on two opposite sides of the can with air-injecting pipe in one of said pockets. This view shows the block of ice completely formed in this construction of can. Fig. 7 is a top plan view

of a modified form of the can showing a block of ice formed therein.

Referring to the drawings, in which like numbers of reference designate like parts throughout, 1 is an open top metallic can, made for example of suitable sheet metal, and with a slight taper toward the bottom so as to facilitate the drawing of the ice-block from the can. The bottom 2 of the can is formed with a depending flange 3 extending around the four sides thereof, and it is secured water-tight to the lower edges of the four sides of the can by means of rivets 4 and solder.

In constructing the can, one piece of sheet metal may be used to form three of the sides 5, 6 and 7 and the fourth side 8 may be made of a single piece flanged at each of its side edges 9 and 10 so as to embrace the free edges of the sides 5 and 7. A separate piece of sheet metal 11 of suitable size has its side edges flanged at 12 and 13 and near its bottom it is formed with a shoulder 14 with a depending flange 15. This piece of sheet metal is placed upon one of the sides of the can, preferably the side 8, so that the flanges 12 and 13 thereof lie against the flanges 9 and 10 respectively of the side 8. These parts are then secured together by means of suitable rivets 16 and 17 which pass through the flanges and likewise the edges of the sides 5 and 7 of the can so that one set of rivets serves to hold these three parts together, and with the use of solder these joints are made water-tight. The bottom flange 15 of the pocket-forming piece of sheet metal 11 is secured to the lower edge of the side 8 of the can by the series of rivets 4 which have already been described, and this joint is likewise soldered to make it water-tight.

If preferred, the four sides of the can may be formed from one piece of sheet metal as indicated in Fig. 5, and also Fig. 7, in which construction but one side seam in the can is necessary, and this may be made at one of the corners where the pocket is located. If desired, however, the can may be made in the ordinary way in which a single sheet of metal is used for each of the four sides with a riveted and soldered seam extending down each corner of the can.

The pocket formed on the can is watertight and it provides upon its interior an air space 18 which extends practically over the entire side in the construction shown herein, though the area of the pocket may be more or less contracted in respect to the width of the side of the can upon which it is

located. The air space of this pocket may be comparatively narrow, and yet it will serve to insulate or retard the freezing action within the zone of the pocket, when the can is placed in the freezing-mixture for the purpose of freezing the water contained in the can.

In Fig. 5, in which the can is shown as having its four sides formed of one piece of sheet metal, the pocket 18 is made by having the sheet metal piece 11^a with its flanged edges placed within the can and riveted and soldered in place as hereinbefore described.

In Fig. 6 I show the can provided with an additional air pocket 19 upon the opposite side of the can from the pocket 11. In Fig. 7 the can 1^a, is made one-half of the width of the can shown in the other figures and is provided at one end with the air-pocket 18. Within the air-pocket 18 is arranged an air-injecting pipe 20 which is suitably secured to the side of the can and has its lower end threaded and screwed into a threaded channel 21 formed in a fixture 22 which is made fast to the side of the can within the pocket and near the bottom thereof. The channel 21 is in communication with the interior of the can by means of an aperture or duct 23, and the channel 21 is continued below the level of the duct 23, so as to form a cavity or catch-all 24 in which foreign matter contained in the air may accumulate. The upper end of the air pipe 20 is provided with an elbow piece 25 which is removably secured thereto by means of a friction joint or otherwise. This air-pipe 20 is secured substantially on the center line of the side of the can within the pocket, and when in operation, the elbow 25 is coupled with the air supply pipe, which is generally a flexible tube, as shown at 26 in Fig. 3.

In Fig. 5, I show a modified form of the air pipe 20^a, which is constructed of sheet metal bent into a trough-shaped structure with side flanges 27 and 28 and a bottom flange 29, where the trough-shaped member is closed, the respective flanges of the trough-shaped member being riveted and soldered water-tight to the exterior of the side of the can. At suitable points on a vertical line in the center of the side of the can, I form small perforations 30 for placing the interior of the air-duct 20^a in communication with the interior of the can, so that a series of air jets may be introduced into the can in a vertical plane. Where the series of air injecting openings 30 are used, as soon as the lowermost one is closed by the formation of the ice the ones above it continue in use and so on through the series of openings. In this way the air may be injected into the body of water from which the ice is formed until practically all of the body of water is frozen.

In Fig. 3 I show my improved can as placed within an ordinary freezing tank 31 containing a freezing medium 32 which is usually brine at a low temperature which temperature is created and maintained by the use of ordinary ammonia pipes which are not shown. In this figure, the ice-block 33 is shown as practically completed and in this condition the can may be removed from the tank and the ice-block drawn from the can. A further freezing, however, will reduce the size of the central cavity or core 34 of the ice-block and cause it to assume substantially the dimensions as shown in Fig. 4. This, however, is a matter of expediency and depends upon whether the freezing process be shortened or prolonged, and in cases where it is prolonged until all the water in the can is frozen, the core contains what is known as white ice instead of being constituted by a narrow space or pocket in the center of the ice-block, as is the case where the freezing process is shortened. Throughout the freezing action air is introduced into the body of water from which the ice is formed, from a pipe 26 which is connected with the elbow 25 of the air injecting pipe 20, and it is forced into the body of water through the duct or opening 23 located in the lower part of the can on the center line of the pocketed-side thereof. The air is thus introduced for the well known purpose of slightly agitating the ice-forming water during the process of freezing in order to produce clear ice.

In the use of this ice can, as just described, the freezing action takes place with full and substantially uniform effect upon all the exposed or uninsulated sides of the can, but it is retarded in the vicinity where the air or insulating pocket is located and where the air is injected into the can, with the result that the last portion of the ice-forming water that is frozen is that located substantially in the plane that is vertical and central in respect to one horizontal dimension of the ice-block. This unfrozen portion or core 34 is thus centralized in a vertical plane in the ice-block and where one pocket only is used the core or space 34 is located nearer to the insulated or pocketed side of the can than it is to the opposite side. Where, however, the can is provided with pockets upon two opposite sides as shown in Fig. 6, the core or cavity 34 is substantially an equal distance from each pocketed side and is of course centralized between the two opposite uninsulated sides of the can. Where the commercial size of the ice-cake is about forty inches deep by about twenty-three inches by eleven inches in its other two dimensions, I make the can of sufficient depth to have the ice-block forty inches deep, and I make the horizontal dimensions of the can about twenty-three inches by twenty-two

inches and arrange the air-pocket on the twenty-two inch side of the can. In making the ice-block in this can, the core 34 being centralized as described, when the 5 block is removed from the can, I cut the ice-block in half, on substantially the center line of the core, using the plane of the core as the cutting line, and I thereby obtain two commercial sized cakes of clear ice which is 10 free from core ice. Where, however, the more desirable clear cake of ice is not demanded, and it is not objectionable to have the commercial cake contain a core or cavity, I make the pocketed-can about half of the 15 twenty-two inch horizontal dimension, namely eleven inches, as shown in Fig. 7, leaving the other dimensions as described, and in this can there may be formed one cake of ice 35, of commercial size, with the 20 core 34 incorporated in the cake, and which core is left in the cake. The air pipe 20 which I have herewith shown passes through an opening in the lug or bracket 39 on the side of the can near the upper end thereof 25 and makes a snug fit therewith in order to hold it fast. The pipe may also be soldered in place if desired.

I find from the use of this can that by making the cross-sectional area of the ice-block substantially equal to twice the cross-sectional area of the commercial size of ice-cake, that the time required to freeze such a block is considerably lessened in proportion to that required where the ice-block is made 30 more than twice the cross-sectional area of the commercial sized cake. Furthermore, by having the can with its insulating-pocket and its air-injecting pipe forming a permanent part of the structure, so that the described parts constitute a unitary commercial article, much time and labor is saved in handling the cans when the ice is harvested or drawn from the cans, for in the construction where an independent or separate 35 air-injecting pipe is employed and the same is suspended within the ice-can, it requires separate handling and careful adjustment to locate the pipe in its proper place to prevent its being prematurely frozen into the ice-block, and when it is frozen in the ice-block considerable difficulty results in having to thaw or cut it out of the block. It will also be observed that by virtue of having the air-pipe located within the pocket, 40 the pipe is not only protected from the action of the brine during the freezing process, but it is also protected from injury when the cans are removed from the freezing-tank and manipulated in the removal of the ice-block, for the pipe is completely housed by the pocket. Another most important advantage of this improved can is that the ordinary service water in what is called raw condition, that is undistilled, may be used for 45 making the block of ice from which may be

cut commercial sized cakes of ice that are clear.

It will be understood that I do not limit my invention to the particular constructions herein shown, as various modifications may 70 be made therein, without, however, departing from the spirit of my invention.

Having thus described my invention what I claim and desire to secure by Letters Patent is:

1. As a new article of manufacture, a can 75 in which ice is artificially made and provided upon one or more of its sides and above the bottom with means for excluding the freezing medium substantially from such side or 80 sides and retarding the freezing process at such side or sides when the can with its contents is subjected to the freezing medium, and an air-injector located upon one of said sides having the freezing retarding means 85 above the bottom and acting to introduce air into the water in said can, substantially as described.

2. As a new article of manufacture, a can 90 in which ice is artificially made and provided upon one or more of its sides and above the bottom with a pocket substantially coextensive with said side or sides and adapted to contain air and to exclude the freezing medium and serving to retard the freezing of 95 the water within the can in the vicinity of said pocket, the said pocket being formed by a sheet of metal secured to the can and suitably spaced therefrom and extending substantially across the width of the side of the 100 can, and an air injector located upon one of said pocketed sides and acting to introduce air into the water in the can, substantially as described.

3. As a new article of manufacture, a 105 piped can in which ice is artificially made consisting in a can provided upon one or more of its sides with a pocket adapted to contain air and serving to retard the freezing of the water within the vessel in the 110 locality of said pocket, the said pocket being formed by a sheet of material secured to the can and suitably spaced therefrom, and an air-injecting pipe or duct located upon a pocketed-side of said can and suitably secured thereto within the zone of retardation 115 and provided with a series of vertically arranged openings into the interior of the can, substantially as described.

4. As a new article of manufacture, a 120 piped can in which ice is artificially made consisting in a can provided upon one or more of its sides with a pocket adapted to contain air and serving to retard the freezing of the water within the vessel in the 125 locality of said pocket, a fixture secured upon the side of said can near the bottom thereof and within said pocket and provided with a duct passing through said fixture and communicating with the interior of 130

the can, a cavity or catch-all beneath said duct below the level of its opening into the can, an air-channel connected with said duct in said fixture and extending upwardly through said pocket to the upper end thereof and adapted to be connected with an air supply pipe, substantially as described.

5. As a new article of manufacture, a piped can in which ice is artificially made 10 consisting in a can provided upon one or more of its sides with a pocket adapted to contain air and serving to retard the freezing of the water within the locality of said pocket, a fixture secured upon 15 the side of said can and within said pocket and provided with a duct passing through said fixture and communicating with the interior of the can, an air-conduit connected with said duct in said fixture and extending 20 upwardly through said pocket to the upper

end thereof and adapted to be connected with an air supply pipe, substantially as described.

6. As a new article of manufacture, a can 25 in which ice is artificially made and provided upon one or more of its sides with a pocket adapted to contain air and serving to retard the freezing of the water within the can in the vicinity of said pocket, and an air injector located upon one of said pocketed 30 sides and arranged to inject air into the water in the can along a vertical plane, substantially as described.

In testimony whereof, I have hereunto set my hand in the presence of the two 35 subscribing witnesses.

JAMES HUMES.
